Application May 28, 1954, Serial No. 30,731

Term of patent 14 years

(Cl. D48—20)

To all whom it may concern:

Be it known that I, Benoit M. Singleton, have invented a new, original, and ornamental Design for a Combination Porch Light and Grab Bar, of which the following is a specification, reference being had to the accompanying drawing forming a part hereof.

I claim:

The ornamental design for a combination porch light and grab bar, substantially as shown and described.
